COMBINED TELEVISION AND BAR CABINET

James E. Doles, Bronx, N. Y.

Application April 13, 1954, Serial No. 29,977

Term of patent 14 years

(Cl. D56—4)

Fig. 1.

Fig. 2.

Fig. 3.

To all whom it may concern:

Be it known that I, James E. Doles, a citizen of the United States of America, residing at the Bronx, in the county of Bronx and State of New York, have invented a new, original, and ornamental Design of a Combined Television and Bar Cabinet, of which the following is a specification, reference being had to the accompanying drawing, forming a part thereof.

Figure 1 is a front elevational view of a combined television and bar cabinet, showing my new design;

Fig. 2 is a top plan view thereof; and,

Fig. 3 is an end elevational view thereof.

The rear of the combined television and bar cabinet is plain.

I claim:

The ornamental design of a combined television and bar cabinet, as shown and described.
